RECLINING CHAIR OF THE MULTIPLE POSITION TYPE

Fridtjof F. Schliephacke, Berlin-Schmargendorf, Germany, assignor to Anton Lorenz, Boynton Beach, Fla.

Filed July 13, 1960, Ser. No. 42,549

9 Claims. (Cl. 297—321)

The present invention relates generally to reclining chairs of the multiple movement type, and in particular to an improved reclining chair incorporating a body-supporting unit including a movable seat and movable back-rest which are coordinated to each other to establish multiple chair positions.

The recently developed multiple movement chair of the recliner type comprises a support and a body-supporting unit including a movable seat and a movable back-rest which are mounted on the support for first and second movement phases. During the first movement phase, the seat and back-rest move from the sitting position to an intermediate tilted sitting position during which there is substantially no change in the angular relationship between the seat and back-rest; and during the second movement phase the seat and back-rest move from the intermediate sitting position through various reclining positions to a fully reclining position, with a progressive increased in the angular relationship between the seat and back-rest. Such multiple movement chair of the recliner type usually incorporates a leg-rest which is mounted for movement to a substantially elevated leg-supporting position during the first movement phase such as to provide an adequate leg-support for the chair occupant in the intermediate tilted sitting position and in the infinite number of reclining positions during the second movement phase.

There exists the need for relatively simple and compact mechanisms for achieving the coordinated movement of the seat and back-seat during the first and second movement phases. Further, provision should be made in this type of chair to establish the order or sequence of operations of the mechanisms to assure that the body-supporting means will be properly guided during the first and second movement phases respectively to establish the multiple positions for the chair. Such sequencing means for the chair should be of a positive and reliable nature and preferably should be automatically operated when the chair occupant is seated and exerts the necessary actuating force on the body-supporting means of the chair. Still further, the sequencing means should be generally compatible with the more generalized requirements of simplicity and construction and facility for mass production manufacture.

Broadly, it is an object of the present invention to provide an improved recliner type of multiple movement chair which realizes one or more of the aforesaid objectives. Specifically, it is within the contemplation of the present invention to provide a recliner type of multiple movement chair which provides for respective first and second movement phases for the chair, with the initial movement of the body-supporting means to an intermediate tilted position with substantially no angular change between the seat and back-rest, and the further movement of the chair through successive reclining positions with an increase in the angular relationship between the seat and back-rest.

It is a further object of the present invention to provide an improved multiple movement chair of the recliner type which incorporates as part of the coordinating mechanisms thereof a sequencing arrangement which establishes the order of operations for the coordinating mechanisms to assure proper chair operation.

In accordance with an illustrative embodiment demon-

2

strating objects and features of the present invention, there is provided a reclining chair comprising a support and body-supporting means including a seat and back-rest adapted to be mounted on said support for inclining and reclining movement respectively from a sitting position to an intermediate tilted sitting position to a reclining position in a second movement phase. A front seat guiding link is pivotally connected to the seat and means including a lost motion connection providing a front pivotal mount for the front seat guiding link on said support. A rear seat guiding link is pivotally mounted on the support and pivotally connected to the seat, the front and rear seat guiding links serve during the first movement phase to guide the seat upwardly and rearwardly relative to the support to a first inclined position. A back-rest guiding link is pivotally mounted on the support at a pivotal mount and means pivotally connected to the back-rest. Means are provided for blocking lost motion travel of the front guiding link relative to the support during the first movement phase and enables the lost motion travel during the second movement phase. The front and rear seat guiding links cooperate with the back-rest guiding link during said first movement phase to maintain a substantially fixed angular relationship between the seat and back-rest and the front and rear seat guiding links cooperate with the back-rest guiding link during said second movement phase to increase the angular relationship between the seat and back-rest, with the front seat guiding link having a lost motion travel relative to the support and with the seat turning on the pivotal connection to the rear seat guiding link.

The above brief description, as well as further objects, features and advantages of the present invention will be more fully appreciated by reference to the following detailed description of several presently preferred, but nonetheless illustrative embodiments, according to the present invention, wherein:

FIG. 1 is a side elevational view, with parts broken away, of a reclining chair demonstrating features of the present invention, shown in the upright or sitting position;

FIG. 2 is a side elevational view similar to FIG. 1, but showing the chair in its intermediate tilted sitting position;

FIG. 3 is a side elevational view similar to FIG. 1, but showing the chair in a fully reclined position;

FIG. 4 is a side elevational view of another embodiment of a reclining chair demonstrating further features of the invention, shown in the upright or sitting position;

FIG. 5 is a side elevational view similar to FIG. 4, but showing the chair in the intermediate tilted sitting position; and,

FIG. 6 is a side elevational view similar to FIG. 4, but showing the chair in a fully reclined position.

Referring now specifically to FIGS. 1 to 3 of the drawings, there is shown a reclining chair, generally designated by the reference numeral 10, which includes a chair frame or support 12 having opposite side walls 14, 16 interconnected by a number of cross braces 18 and supported on depending legs 20. A body-supporting means or unit including a back-rest 22 and the seat 24 are mounted on the support for reclining and inclining movement respectively through a first movement phase from the upright or sitting position illustrated in FIG. 1 to the intermediate tilted position illustrated in FIG. 2

and for a second movement phase from the intermediate tilted sitting position illustrated in FIG. 2 through a series of reclining positions to the fully reclined position illustrated in FIG. 3. In the interest of simplicity, there is no showing of the leg-rest and its mounting and controlled arrangement which is usually found in a chair of this type. However, it will be appreciated that such

leg-rest will be incorporated in the chair which leg-rest moves to an elevated leg-supporting position as the body-supporting means moves into the intermediate tilted sitting position illustrated in FIG. 2. Effectively the leg-rest provides a support for the legs of the chair occupant as the chair is moved from the intermediate tilted sitting position through the various reclining positions to the fully reclined positions illustrated in FIG. 3. The details of such leg-rest and its mounting and control arrangement, as well as its incorporation into the present chair, will be generally understood to those skilled in the art and typical arrangement may be found in the prior art patents of the assignee herein.

Seat guiding means are operatively connected between the support 12 and the seat 24 for imparting a first inclination to the seat during the first movement phase, as may be seen in FIGS. 1 and 2, and for imparting a second inclination to the seat during the second movement phase, as may be seen by comparing FIGS. 2 and 3. The seat guiding means includes a front seat guiding link 26 which is upwardly and forwardly inclined and has a front pivotal connection 28 to the seat 24. Means including a lost motion connection provide a front pivotal mount for the front seat guiding link 26 on the support 12. In this illustrative embodiment, a mounting bracket 30 is fixed to the chair frame or support 12 (i.e. at the cross brace 18) and carries a pin 32 which is confined within an elongated slot 34 formed within the lower end portion of the front seat guiding link 26. The pin 32 remains at the upper end of the slot 34 during the first movement phase and provides the front pivotal mount for the front seat guiding link 26. During the second movement phase, there is a lost motion travel between the pin and slot interconnection 32, 34, with the link 26 translating upwardly such that the pin 32 is confined at the lower end of the slot in the fully reclined position illustrated in FIG. 3. The seat guiding means further includes a rear seat guiding link 38 which is upwardly and forwardly inclined and has a rear pivotal connection 40 at its upper end to the seat 24 at a location spaced rearwardly of the front pivotal connection 28. The rear seat guiding link 38 has a rear pivotal mount 42 on the support 12 provided by an appropriate bracket 44. The front and rear seat guiding links 26, 38, serve during the first movement phase to guide the seat upwardly and rearwardly relative to the support to a first inclined position and during the second movement phase to guide the seat 24 to a second inclined position, with the front seat guiding link 26 having a lost motion travel relative to the support 12, and with the seat 24 turning on the rear pivotal connection 40.

Turning now to the back-rest mounting and guiding arrangement, the back-rest 22 is pivotally mounted on the seat 24 at a back-rest pivot 46 such that the back-rest may move substantially as a unit with the seat 24 during the first movement phase and recline relative to the seat 24 during the second movement phase to increase the angular relationship therebetween. Spaced forwardly of the back-rest pivot 46 is a back-rest guiding link 48 which in this illustrative embodiment is forwardly and downwardly inclined. At its upper end the back-rest guiding link 48 has a pivotal mount 50 on the support provided by an appropriate bracket 52, and at its lower end the back-rest guiding link 48 has a pivotal connection 54 to the forwardly projecting extension of the back-rest pivot 46. The back-rest guiding link 48 cooperates with the seat guiding links 26, 38 during the first movement phase to maintain a substantially fixed angular relationship between the seat 24 and the back-rest, and during the second movement phase to increase the angular relationship between the seat and back-rest.

Provision is made for blocking or precluding lost motion travel of the front guiding link 26 relative to the support 12 during the first movement phase and for

enabling such lost motion travel during the second movement phase. The blocking or sequencing means includes a double-arc slot 56 formed on the mounting bracket 30 adjacent the front seat guiding link 26 and guidingly engaging a pin 58 fixed to the lower end of the front seat guiding link 26. The double-arc slot 56 includes a first slot section 56a merging with a second slot section 56b at a junction 56c. The pin 58 is at the end of the first slot section 56a remote from the junction 56c in the sitting position of the chair and translates along the first slot section 56a during the first movement phase, as may be appreciated by comparing FIGS. 1 and 2. The curvature of the first slot section 56a is selected at a radius about the pivotal mount 32 (such radius being measured between the pins 32, 58) to confine the front seat guiding link 26 to turning movement about the front pivotal mount 32 while at the upper end of the lost motion slot 34. The second slot section 56b is substantially aligned with the lost motion slot 34 when the chair is in the intermediate tilted sitting position of FIG. 2, and is of an appropriate curvature to enable the lost motion travel of the pin and slot interconnection 32, 34 during the second movement phase such that the front seat guiding link 26 may translate upwardly relative to the support, as may be appreciated by comparing FIGS. 2 and 3.

Appropriate stops are provided to establish the several chair positions, as is generally understood. Specifically, the seat guiding means is blocked in the intermediate tilted sitting position by a stop 60 fixed to the chair frame or support 12 behind the rear seat guiding link 38 to block clockwise turning movement thereof about the rear pivotal mount 42 when the chair arrives at the intermediate tilted sitting position of FIG. 2. Thereafter, and as previously indicated, there is a turning movement of the seat about the rear pivotal connection 40 with a corresponding lost motion of the front seat guiding link 26 relative to the support to the fully reclined position of FIG. 3. In this illustrative embodiment, the fully reclined position is established by contact of the lower end of the back-rest 22 with the rear cross brace 18 serving as a stop.

A typical sequence of operations will now be described to facilitate a more thorough understanding of the present invention:

As the chair occupant leans against the back-rest 22 and pushes rearwardly, the seat 24 will be guided by the seat guiding means which includes a four-bar seat guiding linkage having as movable links thereof the front seat guiding link 26, the portion of the seat 24 intermediate the front and rear pivotal connections 28, 40, and the rear seat guiding link 38, and as the stationary link thereof the portion of the support intermediate the front and rear pivotal mounts 32, 42. During such first movement phase, the guiding action on the back-rest 22 from the back-rest guiding link 48 is such as to maintain a substantially fixed relationship to the seat 24, with the body-supporting unit moving into the intermediate tilted sitting position illustrated in FIG. 2 wherein further turning movement in the clockwise direction of the rear seat guiding link 38 is precluded by the stop 60. Thereupon, continued pressure by the chair occupant against the back-rest 22 will cause the turning movement of the seat 24 about the rear pivotal connection 40 with a concurrent lost motion travel of the front seat guiding link 26 relative to the support. During such second movement phase, the guiding action of the back-rest guiding link 48 on the back-rest 22 is such as to open up the angle between the seat and back-rest, as shown in FIGS. 2 and 3, with the fully reclined position being established when the lower end of the back-rest 22 contacts the rear cross brace 18.

Referring now specifically to FIGS. 4 to 6 of the drawings, there is shown a further embodiment of reclining chairs, generally designated by the reference numeral 110,

which includes a chair frame or support 112 having opposite side walls 114, 116 interconnected by a number of cross braces 118 and supported on depending legs 120. A body-supporting means or unit including a back-rest 122 and the seat 124 are mounted on the support for reclining and inclining movement respectively through a first movement phase from the upright or sitting position illustrated in FIG. 4 to the intermediate tilted position illustrated in FIG. 5 and for a second movement phase from the intermediate tilted sitting position illustrated in FIG. 5 through a series of reclining positions to the fully reclined position illustrated in FIG. 6. Again, in the interest of simplicity, there is no showing of the leg-rest and its mounting and controlled arrangement which is usually found in the chair of this type.

Seat guiding means are operatively connected between the support 112 and the seat 124 for imparting a first inclination to the seat during the first movement phase, as may be seen in FIGS. 4 and 5, and for imparting a second inclination to the seat during the second movement phase, as may be seen by comparing FIGS. 5 and 6. The seat guiding means includes a front seat guiding link 126 which is upwardly and forwardly inclined and has a front pivotal connection 128 to the seat. A mounting bracket 130 is fixed to the chair frame or support 112 (i.e. at the cross brace 118) and carries a pin 132 which is confined within an elongated slot 134 formed within the lower end portion of the front seat guiding link 126. The pin 132 remains at the upper end of the slot 134 during the first movement phase and provides a front pivotal mount for the front seat guiding link 126. During the second movement phase, there is a lost motion travel between the pin and slot interconnection 132, 134, with the link 126 translating upwardly such that the pin 132 is confined at the lower end of the slot in the fully reclined position illustrated in FIG. 6. The seat guiding means further includes a rear seat guiding link 138 which is upwardly and forwardly inclined and has a rear pivotal connection 140 at its upper end to the seat 124 at a location spaced rearwardly of the front pivotal connection 128. The rear seat guiding link 138 has a rear pivotal mount 142 on the support 112 provided by an appropriate bracket 144. The front and rear seat guiding links 126, 138 serve during the first movement phase to guide the seat upwardly and rearwardly relative to the support to a first inclined position, and during the second movement phase to guide the seat 124 to a second inclined position, with the front seat guiding link 126 having a lost motion travel relative to the support 112, and with the seat 124 turning on the rear pivotal connection 140.

Turning now to the back-rest mounting and guide arrangement, the back-rest 122 is pivotally mounted on the seat 124 at a back-rest pivot 146 such that the back-rest may move substantially as a unit with the seat 124 during the first movement phase and recline relative to the seat 124 during the second movement phase to increase the angular relationship therebetween. Spaced forwardly of the back-rest pivot 146 is a back-rest guiding link 148, which in this illustrative embodiment is upwardly and forwardly inclined. At its lower end the back-rest guiding link 148 has a pivotal mount 150 on the support provided by an appropriate bracket 152, and at its upper end the back-rest guiding link 148 has a pivotal connection 154 to the forwardly projecting extension of the back-rest 122 at a location forwardly of the back-rest pivot 146. The back-rest guiding link 148 cooperates with the seat guiding links 126, 138 during the first movement phase to maintain a substantially fixed angular relationship between the seat 124 and the back-rest 122, and during the second movement phase to increase the angular relationship between the seat and back-rest.

Provision is made for blocking or precluding lost motion travel of the front guiding link 126 relative to the

support 112 during the first movement phase and for enabling such lost motion travel during the second movement phase. The blocking or sequencing means includes a double-arc'd slot 156 formed on the mounting bracket 130 adjacent the front seat guiding link 126 and guidingly engaging a pin 158 fixed to the lower end of the link 126. The double-arc'd slot 156 includes a first slot section 156a merging with a second slot section 156b at a junction 156c. The pin 158 is at the end of the first slot section 156a remote from the junction 156c in the sitting position of the chair and translates along the first slot section 156a during the first movement phase, as may be appreciated by comparing FIGS. 4 and 5. The curvature of the first slot section 156a is selected at a radius about the pivotal mount 132 to confine the front seat guiding link 126 to turning movement about the front pivotal mount 132 while at the upper end of the lost motion slot 134. The second slot section 156b is substantially aligned with the lost motion slot 134 when the chair is in the intermediate tilted sitting position of FIG. 5 and is of an appropriate curvature to enable the lost motion travel of the pin and slot interconnection 132, 134 during the second movement phase such that front seat guiding link 126 may translate upwardly relative to the support, as may be appreciated by comparing FIGS. 5 and 6.

Appropriate stops are provided to establish the several chair positions, as is generally understood. Specifically, the seat guiding means is blocked in the intermediate tilted sitting position by a stop 160 fixed to the chair frame or support 112 behind the rear seat guiding link 138 to block clockwise turning movement thereof about the rear pivotal mount 142 when the chair arrives at the intermediate tilted sitting position of FIG. 5. Thereafter, there is a turning movement of the seat about the rear pivotal connection 140 with a corresponding lost motion of the front seat guiding link 126 relative to the support until the chair arrives at the fully reclined position. In this illustrative embodiment, the fully reclined position is established by contact of the lower end of the back-rest 122 with the rear cross brace 118 serving as a stop.

A latitude of modification, change and substitution is intended in the foregoing disclosure and in some instances some features of the invention will be employed without a corresponding use of other features. Accordingly, it is appropriate that the appended claims be construed broadly and in a manner consistent with the spirit and scope of the invention herein.

What I claim is:

1. A reclining chair comprising a support, a body-supporting means including a seat and back-rest adapted to be mounted on said support for inclining and reclining movement respectively from a sitting position to an intermediate tilted sitting position during a first movement phase and from said intermediate tilted sitting position to a reclining position during a second movement phase, a front seat guiding link pivotally connected to said seat, means including a lost motion connection providing a front pivotal mount for said front seat guiding link on said support, a rear seat guiding link pivotally mounted on said support and pivotally connected to said seat, means pivotally mounting said back rest on said seat at a back-rest pivot, a back-rest guiding link, means pivotally mounting said back-rest guiding link on said support at a pivotal mount, means pivotally connecting said back-rest guiding link to said back-rest at a location spaced from said back-rest pivot, and means for blocking lost motion travel of said front guiding link relative to said support during said first movement phase and for enabling said lost motion travel during said second movement phase.

2. A reclining chair comprising a support, a body-supporting means including a seat and back-rest adapted to be mounted on said support for inclining and reclining movement respectively from a sitting position to an intermediate tilted sitting position during a first movement phase and

from said intermediate tilted sitting position to a reclining position during a second movement phase, a front seat guiding link pivotally connected to said seat, means including a lost motion connection providing a front pivotal mount for said front seat guiding link on said support, a rear seat guiding link pivotally mounted on said support and pivotally connected to said seat, said front and rear seat guiding links serving during said first movement phase to guide said seat upwardly and rearwardly relative to said support to a first inclined position, means pivotally mounting said back-rest on said seat at a back-rest pivot, a back-rest guiding link, means pivotally mounting said back-rest guiding link on said support at a pivotal mount, means pivotally connecting said back-rest guiding link to said back-rest at a location spaced from said back-rest pivot, and means for blocking lost motion travel of said front guiding link relative to said support during said first movement phase and for enabling said lost motion travel during said second movement phase, said front and rear seat guiding links cooperating with said back-rest guiding link during said first movement phase to maintain a substantially fixed angular relationship between said seat and back-rest during said first movement phase, said front and rear seat guiding links cooperating with said back-rest guiding link during said second movement phase to increase the angular relationship between said seat and back-rest with said front seat guiding link having a lost motion travel relative to said support and with said seat turning on the pivotal connection to said rear seat guiding link.

3. A reclining chair according to claim 2 wherein said back-rest guiding link is downwardly and forwardly inclined in said sitting position and said pivotal mount is at the upper end of said back-rest guiding link.

4. A reclining chair according to claim 2 wherein said back-rest guiding link is upwardly and forwardly inclined in said sitting position and said pivotal mount is at the lower end of said back-rest guiding link.

5. In a reclining chair, a support, body-supporting means including a seat and back-rest adapted to be mounted on said support for inclining and reclining movement respectively from a sitting position to an intermediate tilted sitting position during a first movement phase and from said intermediate tilted sitting position to a reclining position during a second movement phase, means pivotally mounting said back-rest on said seat at a back-rest pivot, seat guiding means including a front seat guiding link pivotally connected to said seat and a lost motion connection providing a front pivotal mount for said front seat guiding link on said support, said seat guiding means serving during said first movement phase to guide said seat upwardly and rearwardly relative to said support to a first inclined position, and back-rest guiding means pivotally mounted on said support and pivotally connected to said back-rest.

6. A reclining chair comprising a support, body-supporting means including a seat and back-rest adapted to be mounted on said support for inclining and reclining movement respectively from a sitting position to an intermediate tilted sitting position during a first movement phase and from said intermediate tilted sitting position to a reclining position during a second movement phase, means pivotally mounting said back-rest on said seat at a back-rest pivot, seat guiding means including a front seat guiding link pivotally connected to said seat and a lost motion connection providing a front pivotal mount for said front seat guiding link on said support, said seat guiding means serving during said first movement phase to guide said seat upwardly and rearwardly relative to said support to a first inclined position, back-rest guiding means pivotally mounted on said support and pivotally connected to said back-rest, and means for blocking lost motion travel of said front guiding link relative to said support during said first movement phase and enabling said lost motion travel during said second movement phase, said seat guiding means cooperating with said

5 back-rest guiding means during said first movement phase to maintain a substantially fixed angular relationship between said seat and back-rest, said seat guiding means cooperating with said back-rest guiding means during said second movement phase to increase the angular relationship between said seat and back-rest with said front seat guiding link having a lost motion travel relative to said support.

7. A reclining chair comprising a support, body-supporting means including a seat and back-rest adapted to be mounted on said support for inclining and reclining movement respectively from a sitting position to an intermediate tilted sitting position during a first movement phase and from said intermediate tilted sitting position to a reclining position during a second movement phase, means pivotally mounting said back-rest on said seat at a back-rest pivot, seat guiding means including a front seat guiding link pivotally connected to said seat and a lost motion connection providing a front pivotal mount for said front seat guiding link on said support, said seat guiding means serving during said first movement phase to guide said seat upwardly and rearwardly relative to said support to a first inclined position, back-rest guiding means pivotally mounted on said support and pivotally connected to said back-rest, and means intermediate said support and said front seat guiding link for blocking lost motion travel of said front guiding link relative to said support during said first movement phase and enabling said lost motion travel during said second movement phase, said blocking means including a double-arched slot and a pin engaged therein, said double-arched slot including at least a first section on a radius about said front pivotal mount.

8. In a reclining chair, a support, body-supporting means including a seat and a back-rest pivotally mounted thereon at a back-rest pivot, seat guiding means operatively connected to said seat including a front seat guiding link, means including a lost motion connection movably mounting said front seat guiding link on said support and providing a front pivotal mount, means pivotally connecting said front seat guiding link to said seat at a front pivotal connection, and a rear seat guiding link pivotally mounted on said support at a rear pivotal mount and pivotally connected to said seat at a rear pivotal connection, said front and rear seat guiding links and the portion of said seat intermediate said front and rear pivotal connection serving as three movable links of a four-bar seat guiding linkage during a first movement phase with said support serving as a stationary link thereof, a back-rest guiding link pivotally mounted on said support at a back-rest pivotal mount and pivotally connected to said back-rest at a back-rest guiding pivotal connection, said back-rest guiding link being operative to guide said back-rest during said first movement phase in a first relationship to said seat and being included in a first back-rest guiding linkage which is constrained by said seat guiding linkage and includes said rear seat guiding link, said seat intermediate said rear pivotal connection and said back-rest pivot, said back-rest intermediate said back-rest pivot and said back-rest guiding pivotal connection and said back-rest guiding link as four movable links thereof and said support intermediate said rear pivotal mount and said back-rest pivotal mount as a stationary link thereof, said means for blocking said rear guiding link of said seat guiding linkage at the end of said first movement phase such that said seat turns about said rear pivotal connection serving as a stationary pivotal mount during a second movement phase, said back-rest guiding link being operative to guide said back-rest during said second movement phase in a second relationship to said seat and being included in a second back-rest guiding linkage which is constrained and includes said seat intermediate said rear pivotal connection and said back-rest pivot as one movable link thereof, said back-rest intermediate said back-rest pivot and said back-rest guiding pivotal connection as a sec-

ond movable link thereof, and said back-rest guiding link as a third movable link thereof and said support and rear guiding link intermediate said back-rest pivotal mount and said rear pivotal connection as a stationary link thereof.

9. In a reclining chair, a support, body-supporting means including a seat and a back-rest pivotally mounted thereon at a back-rest pivot, seat guiding means operatively connected to said seat including a front seat guiding link, a lost motion connection including a pin and slot movably mounting said front seat guiding link on said support and providing a front pivotal mount, means pivotally connecting said front seat guiding link to said seat at a front pivotal connection, and a rear seat guiding link pivotally mounted on said support at a rear pivotal mount and pivotally connected to said seat at a rear pivotal connection, said front and rear seat guiding links and the portion of said seat intermediate said front and rear pivotal connections serving as three movable links of a four-bar seat guiding linkage during a first movement phase with said support serving as a stationary link thereof, a back-rest guiding link pivotally mounted on said support at a back-rest pivotal mount and pivotally connected to said back-rest at a back-rest guiding pivotal connection, said back-rest guiding link being operative to guide said back-rest during said first movement phase in a first relationship to said seat and being included in a first back-rest guiding linkage which is constrained by said seat guiding linkage and includes said rear seat guiding link, said seat intermediate said rear pivotal connection and said back-rest pivot, said

back-rest intermediate said back-rest pivot and said back-rest guiding pivotal connection and said back-rest guiding link as four movable links thereof and said support intermediate said rear pivotal mount and said back-rest pivotal mount as a stationary link thereof, and means for blocking said rear guiding link of said seat guiding linkage at the end of said first movement phase such that said seat turns about said rear pivotal connection serving as a stationary pivotal mount during a second movement phase, said back-rest guiding link being operative to guide said back-rest during said second movement phase in a second relationship to said seat and being included in a second back-rest guiding linkage which is constrained and includes said seat intermediate said rear pivotal connection and said back-rest pivot as one movable link thereof, said back-rest intermediate said back-rest pivot and said back-rest guiding pivotal connection as a second movable link thereof, and said back-rest guiding link as a third movable link thereof and said support and rear guiding link intermediate said back-rest pivotal mount and said rear pivotal connection as a stationary link thereof.
